UNITED STATES PATENT OFFICE.

DANIEL J. MITCHELL, OF ALBUQUERQUE, NEW MEXICO.

WINDING-INDICATOR FOR CLOCKS AND THE LIKE.

1,189,607.

Specification of Letters Patent.

Patented July 4, 1916.

Application filed April 10, 1915, Serial No. 20,538. Renewed December 27, 1915. Serial No. 68,918.

To all whom it may concern:

Be it known that I, DANIEL J. MITCHELL, a citizen of the United States, residing at Albuquerque, in the county of Bernalillo and 5 State of New Mexico, have invented certain new and useful Improvements in Winding-Indicators for Clocks and the like, of which the following is a specification, reference being had to the accompanying drawings.

10 This invention relates to certain improvements in winding indicators for clocks and the like; and it is an object of my invention to provide a novel and improved device of this general character coacting with the 15 winding shaft of the operating spring and serving to give indication, before the spring runs down, that said spring should be rewound.

It is also an object of my invention to provide 20 two rotatably supported members, one of said members being operatively engaged with the winding shaft of the operating spring and the second of said members being capable of a limited independent rotation, 25 both of said members being provided with coacting means whereby they may be caused to operate in unison.

It is also an object of my invention to provide 30 a device of this general character comprising two relatively movable members mounted for rotation upon the hour sleeve of a clock or the like, one of said members being positively driven and the second of said members being capable of limited axial 35 rotation by gravity.

The invention consists in the details of construction and in the combination and arrangement of the several parts of my improved winding indicator for clocks and the 40 like whereby certain important advantages are attained and the device is rendered simpler, less expensive and otherwise more convenient and advantageous for use, all as will be hereinafter more fully set forth.

45 The novel features of the invention will be carefully defined in the appended claims.

In order that my invention may be the better understood, I will now proceed to describe the same with reference to the accompanying drawings, wherein—

Figure 1 is a view in front elevation of a

clock constructed in accordance with an embodiment of my invention; Fig. 2 is a vertical sectional view of the clock as disclosed in Fig. 1 and illustrating in detail the connection between the winding shaft and a rotatable member as herein embodied; Fig. 3 is a fragmentary view in side elevation of the clock works illustrating the features of my invention as disclosed in Fig. 2; Fig. 4 is a 60 sectional view taken substantially on the line 4—4 of Fig. 3; and Fig. 5 is an elevational view, detached, of the second rotatable or indicating member as herein included.

As disclosed in the accompanying drawings, 65 1 denotes the winding shaft of a conventional main spring of a clock or the like, and 2 denotes an hour sleeve operatively engaged with the shaft 1 in a well known way.

Suitably mounted upon the sleeve 2 and 70 capable of freely rotating therearound is a wheel 3 of predetermined diameter and having its toothed periphery 4 in mesh with a pinion 5 fixed to the shaft 1. The ratio of the wheel 3 and pinion 5 is determined, as 75 80 believed to be clearly apparent to those skilled in the art to which my invention appertains, by the duration of time the clock or the like is adapted to run under the influence of the main spring. The wheel 3 has produced 85 therein an arcuate slot 6 preferably in excess of a semi-circle and extending substantially entirely around the wheel and concentric to its axis and extending within said slot is a lug or extension 7 projecting 90 from the rear face of the disk 8 also loosely mounted upon the hour sleeve 2 and provided on its opposite face with an indication 9 adapted to be exposed through the opening 10 produced in the dial 11 of the clock. 95 The outer surface of the disk 8, except the portion provided with the indication 9, is preferably of the same color as the outer face of the dial while the portion 12 of the disk adapted to be exposed through the opening 10 when the indication 9 is in register therewith is of a differing color, as for instance red, so that attention will be more readily directed to the exposed indication.

At a predetermined point on its periphery, 100 the disk 8 is provided with a substantially radial extension 14 which is adapted

to coact with the suitably positioned stops 15 whereby the extent of rotation of the disk 8 in either direction may be properly limited, said stops being herein disclosed 5 as projecting from an adjacent side or plate of the clock works.

The extension 14 is preferably weighted so that the disk 8 may be caused to automatically rotate a limited extent independently 10 of the wheel 3 after the extension 14 has been moved past a vertical center whereby it will be perceived that the indication 9 will be brought into register with the opening 10 at a predetermined time in advance 15 of the time when the main spring will be entirely run down so that an indication of a sufficient period will be afforded in which to rewind the spring without the clock or the like stopping. It will also be observed 20 that the lug or extension 7 is so positioned within the slot 6 as to permit rotation of the wheel in either direction to a degree equal to the extent of said slot before the disk 8 is caused to move or rotate under 25 the influence of said wheel 3.

When the main spring of the clock is wound, the wheel 3 is caused to rotate, and an end of the slot 6 therein will engage the lug or extension 7 on the disk 8 before the 30 winding operation is completed and carry the extension 14 beyond a vertical center when said disk will rotate by gravity until said extension 14 contacts with a stop 15. As the spring runs down the operation is 35 reversed and on such reverse movement of the disk 8 the indication 9 is exposed through the opening 10.

From the foregoing description, it is thought to be obvious that a winding indicator for clocks and the like constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof 50 and for this reason I do not wish to be understood as limiting myself to the precise arrangement and formation of the several parts herein shown in carrying out my invention in practice.

55 I claim:

1. In combination with the winding shaft of a clock mechanism, two relatively movable members rotatable about a common axis, one of said members being operatively engaged with the winding shaft, the second 60 of said members being provided with an indication, and coacting means carried by said members whereby the same may be caused to rotate in unison and in the same general direction.

2. In combination with the winding shaft of a clock mechanism, two relatively movable members rotatable about a common axis, one of said members being operatively engaged with the winding shaft, the second 70 of said members being provided with an indication, coacting means carried by said members whereby the same may be caused to rotate in unison and in the same general direction, and means for limiting the movement of the second named member in either direction.

3. In combination with the winding shaft of a clock mechanism, two relatively movable members rotatable about a common 80 axis, one of said members being operatively engaged with the winding shaft, the second of said members being provided with an indication, and coacting means carried by said members whereby the same may be caused to rotate in unison and in the same general direction, said second named member being provided with a weighted mass whereby the same may automatically rotate independently of the first named member.

4. In combination with the winding shaft and the hour sleeve of a clock mechanism, two relatively movable members rotatably supported by the hour sleeve, one of said members being operatively engaged with the winding shaft, the second of said members being provided with an indication, and coacting means carried by said members whereby the same may be caused to rotate in unison and in the same general direction. 95

5. In combination with the winding shaft of a clock mechanism, two relatively movable members rotatable about a common axis, one of said members being operatively engaged with the winding shaft, the second 100 of said members being provided with an indication, coacting means carried by said members whereby the same may be caused to rotate in unison and in the same general direction, said second named member being provided with a weighted extension, and means adapted to coact with said extension for limiting the movement of the second named member in either direction.

6. In combination with the winding shaft 115 of a clock mechanism, two relatively movable members rotatable about a common axis, one of said members being operatively engaged with the winding shaft and provided with an arcuate slot, the second of said members being provided with an indication, and an extension carried by said second member extending through the slot of the first named member whereby said members may be caused to rotate in unison and in the same general direction.

7. In combination with the winding shaft of a clock mechanism, two relatively movable members rotatable about a common axis, one of said members being operatively 120

engaged with the winding shaft and provided with an arcuate slot, the second of said members being provided with an indication, and an extension carried by said second member extending through the slot of the first named member whereby said members may be caused to rotate in unison and in the same general direction, said second member being provided with a weighted

mass whereby the same may rotate independently of the first named member.

In testimony whereof I hereunto affix my signature in the presence of two witnesses.

DANIEL J. MITCHELL.
